19 Claims. (Cl. 257—227)

1 This invention relates to heat exchangers. Among the objects of the invention are:

1. To provide constructions which ensure that for a heat exchange fluid flowing past the outside of heat exchange elements (e. g. tubes) the flow-layers should be so guided that the temperature difference through the heat transferring wall be kept high substantially all over the surface of the heat transferring wall, so that the mean rate of heat-transfer per unit area of heat transferring wall taken over the whole surface should be high, particularly also for cases where the fluid flowing outside the passages has only a small specific heat per unit volume as compared with the fluid flowing inside, or where fluid flowing outside the wall is to have only a small temperature-change as compared to the fluid flowing inside, without undue increases in velocity of flow.

2. To provide a construction which will enable a heat exchanger to transfer large quantities of heat with the fluid flowing outside the heat exchange elements, for example, tubes moving by virtue of the natural convection supported by some external moving means (pump, or the like) or where the fluid moves by virtue of natural convection only, thus dispensing with the external moving means (pump, blower, or the like) without excessive surface area of heat transferring walls. Under this object would fall, for example, a construction of heat exchanger capable of providing air cooling by means of natural convection for large performances, without excessive surface-areas of heat transferring wall.

The following considerations illuminate the ideas underlying this invention:

A "total" mean rate of heat transfer per unit area of heat transferring wall, which is indicative of the overall properties of a heat exchanger, depends on:

(1) On the difference between the mean temperatures taken over the whole effective surface area of heat transferring wall, between the layers of the two fluids flowing in immediate heat exchange proximity to both sides of the heat transferring wall;

(2) On the ratio α between the effective surface-area of heat transferring wall and a total area of heat transferring wall, which is obtained by dividing the volume taken up (not enclosed) by the components of the heat exchanger (including essential parts such as header tanks, guide-walls, and the like) by the thickness of the heat transferring wall.

Accordingly, apart from making provision for

2 making said mean temperature difference between the flowing fluids large, this invention also makes provision for making this factor α as large (as near to unity) as possible.

Further, consider cases in which the fluid flowing outside heat exchange elements is to flow due to natural convection only. Let, for example, layers of this fluid be guided between a row of vertical tubular surfaces and a casing surrounding the same, forming a passage for said fluid with a large U/A ratio, ratio of wetted circumference U to flow-cross-section A , as is necessary if the layer of fluid is to take effective part in the heat exchange. Then, as proved, the natural convection effect will increase the velocity of the layer only up to a certain height of passage, while for a passage of any greater height the velocity of flow will not increase beyond the value attained at that limiting height, due to the friction losses in the passage. This height, up to which the velocity due to natural convection effect still increases, depends on the U/A ratio, and in order to obtain the benefit of the natural convection effect, provision has to be made to remove this layer of fluid from the heat exchanger passage with the large U/A ratio at or below this limiting height, and to guide it into a passage with a smaller U/A ratio, where its velocity increases further due to natural convection effect.

Accordingly, in order to achieve the objects, this invention provides for means whereby, at a position along a flow of a fluid past a heat exchange element in a passage formed, according to this invention, between a row of such heat exchange elements and a guide-casing surrounding same, layers of said fluid which have attained a required change of temperature while flowing in immediate heat exchange proximity with said elements are diverted from the heat transferring wall and led out of said passage, while layers of this fluid which have not yet taken part in the heat exchange and thus substantially still have their initial temperature, are guided into immediate heat exchange proximity with continuations of said heat exchange elements. This is done in order to avoid that further flow of layers which have attained their required temperature in the immediate heat exchange proximity of the element should change the temperature of these layers too far, thus reducing the mean temperature difference through the heat transferring wall, and further, from the point of view of natural convection motion of the fluid, in order that a layer of fluid which may have been given

a speed approaching the maximum possible due to natural convection in the heat exchanger passage with the large U/A ratio, be led out of this passage into a passage with a smaller U/A ratio, in which its velocity can increase again due to the natural convection effect.

The means for producing the aforesaid effect may be reduplicated a required number of times along the total flow-path of a fluid outside heat exchange elements, thus maintaining the temperature difference through the heat transferring wall of these elements all along the total surface of heat transferring wall, thereby making high the mean rate of heat transfer per unit area of heat transferring wall, and where this is required, fully exploiting the natural convection effect for moving said fluid.

In the accompanying drawings, showing some examples:

Fig. 1 is a vertical section through one embodiment of the invention;

Fig. 2 is a plan section along the line II-II of Fig. 1;

Fig. 3 is a partial vertical section through a second embodiment;

Figs. 4 and 5 are a sectional front elevation and a part sectional side elevation respectively of a further embodiment, Fig. 4 being taken on line IV-IV of Fig. 5;

Figs. 6 and 7 are a sectional front elevation and a part sectional side elevation respectively of another embodiment, and Fig. 6 being taken on the line VI-VI of Fig. 7.

In said drawings like parts are denoted by like reference characters.

In the embodiment shown in Fig. 1, 1 denotes a duct which contains a plurality of rows of heat exchange elements such as tubes 2, bathed externally by a first fluid and traversed internally by a second fluid taking part in the heat exchange. Each of these rows is enclosed by a guide casing 3 having an entry 18 at one end and an exit 19 at the other end for said fluid. Each row of tubes 2 also debouches into two header tanks 4 and 5 which are individual to each row of tubes 2 and respectively induced into and lead away from said tubes said second heat exchange fluid.

At various positions along each guide casing 3, said casing is provided with entry slots 6a and exit slots 6b in opposite sidewalls thereof and respectively extending the entire width of the casing, and the upper end of the casing 3 below each entry slot 6a is bent inwards at 7 to form an entry-guide vane whilst the lower end of the casing 3 above each exit slot 6b is bent inwards at 8 at the side opposite the inwardly bent guide vane 7 to form a baffle, the portion 8 constituting a continuation of the guide 7, the vane thus formed contacting the respective tubes 2 round their circumferences. The entry guide means 6a and 7 of each adjacent pair of casings 3 are arranged to face each other whilst the exit guide-means 6b and 8 of each adjacent pair of casings are likewise arranged to face each other.

At the entry end of each alternate space 12b between adjacent casings 3 into which exit guide vanes 8 lead and which is hence denoted an exit-space, baffle plates 9 are disposed. Each baffle plate 9 carries side walls 10 which, together with the plates 9 leave exit-spaces 12b open at their exit ends only. At the outlet end of the other alternate spaces 12a, from which entry guide vanes 7 lead and which are hence called entry-spaces, similar baffle plates 11 are disposed be-

tween alternate pairs of guide casings 3, said baffle plates 11 extending to the walls of the duct 1 and dividing the space 16a in the duct before entry from space 16b after exit.

The aforesaid construction operates as follows:

Assuming that the construction is intended to be used as an air heater, then the entry header tanks 5 will carry a heated liquid, such as hot water, which flows downwards in the tubes 2, and is led out of the heat exchanger by header tanks 4 after having given its heat to the air. The air flowing in the portion 16a of duct 1 flows into each guide-casing 3 at its lower open end 18, flowing in contact (immediate proximity) to the outside of the tubes and taking part in the heat exchange, and on reaching guide-vanes 7 is deflected from the heat transferring wall through slots 6b into exit spaces 12b between alternate pairs of guide-casings 3. In addition the air flows into every other entry-space 12a between alternate pairs of guide-casings 3 from which layers of the air are drawn through slots 6a into contact with the outside of the tubes at different positions along the height of the passage, the respective layers being then led out again into exit-spaces 12b. Air coming into the heat exchanger from below is, however, prevented by baffles 9 and side walls 10 from flowing directly into the spaces 12b, in which flows air which has already taken its part in the heat exchange and baffle 11 prevents exit of air, which has not yet taken part in the heat exchange, from the entry-spaces 12a into the space 16b in the duct 1, leaving only exit holes for the passages 12b into this space, for air which has been heated. Thus the arrangements of walls 10 and baffles 9 and 11 prevent air which has not yet been heated from passing from entry-spaces 12a to exit-spaces 12b, and more generally from space 16a to space 16b except through spaces bringing it into contact with the heat transferring wall.

Thus this construction is seen to effect that layers of the air which have flowed in contact with the heat exchanger tubes over such distances that they have attained their required temperature, are then led away from the heat transferring walls, and replaced on the continuations of the heat transferring walls by fresh layers of air, which still have the initial air-temperature, so that thereby the temperature difference between the air on the outside of the tubes and the hot water inside the tubes is maintained high along the length of the flow, instead of falling too far, as would be the case if the same layer of air remained in contact with the tubes.

Further as regards natural convection, this construction ensures that a layer which has flowed in immediate heat exchange proximity with the heat transferring wall in what is, in effect, a passage with a very large U/A ratio of wetted circumference to flow-cross-section, in which beyond a small limiting height its velocity due to natural convection cannot increase any further, is led away from the heat transferring wall into passage 12b whose U/A ratio is much smaller, so that there the velocity can increase further, the natural convection thus being exploited.

Further, with regard to the uniformity of the heating of the air, layers of air having been heated at the lower end of the tubes where the temperature difference to the already cooled

water is lower, will, in passing up the passage 12b, flow past the exits 6b at both sides from which emerge layers of air which have been heated at higher and higher temperature differences, so that thus the less heated layers of air are mixed with those layers which have been heated to higher temperature, and the air emerges from the tops of passages 12b with substantially uniform temperature.

The arrangement of the tubes 2 in rows, with each row of tubes having header tanks 4 and 5 separately to itself, where the tanks 4 and 5 are staggered for adjacent rows, ensures that the air flows into and out of the spaces between the rows of tubes without substantial change of direction or hindrance, and likewise enters the guide-casings 3 at the bottom without hindrance, such as would be imposed if there were a header tank common to all tubes of all rows. Further due to the relative displacement of tubes in the direction of the flow, air flows into the spaces between the headers 4 of a row sideways from at least one direction, and then, due to the pressure-difference from entry to exit has to flow along the tubes in these spaces between the tubes of the same row, so that by this arrangement of separate header tanks for each row of tubes, which have spaces between them in the plane normal to the flow direction of the air, as well as in the flow-direction, even flow of the air is provided at all positions round the circumference of each tube, and all tubes of the heat exchange are made subject to air flow at the same velocity.

The embodiment illustrated in Fig. 3 is substantially identical with that illustrated in Figs. 1 and 2, with the following exceptions: The tubes 2 are each traversed by a smaller-diameter tube 13 which is open at both ends and passes through headers 4 and 5. The water to be cooled then flows down the annular spaces between the respective tubes 2 and 13, while cooling air also flows upwards through tubes 13. A further feature by which the embodiment of Fig. 3 differs from that of Figs. 1 and 2 is that the duct 1 does not extend beyond the highest peripheral baffle space, so as to permit free access of air to the casings 3 in all directions i. e. both vertically and horizontally, the baffle plates 9 and 11, and side walls 10 of spacer 12b forming a labyrinthine baffle preventing any direct access of air to the spaces 12b traversed by air which has already taken part in the heat exchange. A further difference between the present embodiment and that described with reference to Figs. 1 and 2 is that the duct 1 terminates in a chimney 17 of a substantial height depending on requirements, the function of the chimney being to create an updraught and produce extra velocity past the heat transferring walls. A section is shown between two tubes of a row, indicating air flow there, and a further section through the centre plane of a tube 2, indicating water flow by arrows in the annular space between tube 2 and the inner tube 13, carrying cooling air.

Figs. 4 and 5 show another embodiment in which, instead of one row of tubes comprising vertical tubes 2 running from entry header tank 5 for the hot water at the top to exit header tank 4 at the bottom, there are provided two rows of tubes in the same plane. The top row of tubes is exactly the same as described with reference to Figs. 1 and 2, except that the inner tube 13 in each tube 2 is missing. At the posi-

tions where tubes 2 enter their bottom header tank 31, tube stumps 32 of smaller diameter than the tubes 2 are inserted into the mouths of tubes 2, these stumps 32 continuing through header tanks 31 to form a row of tubes which is again surrounded by a guide-casing 3, similar to the upper row of tubes 2. Tubes 32 at their bottom ends debouch into header tanks 33 for the water. The arrangement of the guide-casings 3 with their entry and exit slots 6a and 6b and the entry and exit passages 12a and 12b formed between them is analogous to that described with reference to Figs. 1 and 2, with the addition that baffles 41 and 42 connecting to tank 31 in spaces 12a and 12b respectively cooperate with baffles 11 and 9 respectively to separate spaces containing air which has not yet taken part in the heat exchange from spaces containing air which has taken part in the heat exchange.

The aforesaid construction operates as follows:

Hot water enters tubes 2 of the top row through header tanks 5 from duct 36 and while flowing down the tubes 2 the outer layers of hot water in the tubes give up heat to the layers of unheated air which are successively guided into contact with the heat transferring wall by guide-casing 3, as described with reference to Figs. 1 and 2.

Before the water enters the intermediate header tank 31, tube stumps 32 separate the inner layers of the flow in each tube, which have substantially retained their original temperature, from the outer layers, which have become cooled, and these outer layers flow into the intermediate header tank 31 and are led from there out of the heat exchanger in duct 34. Meanwhile the still hot inner layers of water flow down tubes 32, where they come into heat exchange proximity with unheated layers of air brought to the heat transferring wall by guide-casing 3 as already described, before being led out of the heat exchanger in header tanks 33, debouching into collector 35.

Figs. 6 and 7 show a further embodiment, the top of which comprises rows of tubes 2 between top header tanks 5 and intermediate header tanks 31, the rows of tubes being surrounded by guide-casings 3, similarly as described with reference to Figs. 4 and 5.

The stumps 32 are inserted into the mouths of tubes 2 before these enter their intermediate header tanks 31, and pass through tanks 31 and lead into a header tank 37. From this header tank 37, a new row of tubes 38 begins, the tubes of this row as seen in Fig. 7 not being on the same centre-lines as the tubes 2 of the row above, but being staggered relatively thereto, the centre-lines, however still lying in the same plane. These tubes 38 lead into exit header tanks 33, and are traversed by internal tubes 39 which pass through both header tanks 37 and 33. The row of tubes 38 is surrounded by a guide casing 3, as previously described. A baffle 40 is provided between the intermediate header tanks 31 and 37 of a row and baffles 41 and 42 in spaces 12a and 12b respectively. The aforescribed construction operates as follows:

Hot water coming from duct 36 is led through header tanks 5 into tubes 2 of a top row, and while flowing down tubes 2, the outer layers of the water in the tubes give up heat to the unheated layers of air which are successively guided into contact with the heat transferring wall by guide-casing 3, as described with reference to Figs. 1 and 2. Tube stump 32 separates the outer layers of the water, which have taken their part

in the heat exchange from the inner layers, which have not, and guides the former into intermediate headers 31, whence they flow out of the heat exchanger through collector 34.

The inner layers of the water, which have substantially retained their original temperature, are led into intermediate header tank 37 from where it flows in the annular spaces between tubes 38 and 39 down to header tank 35. Air flows along the outside of tubes 38, being guided in guide-casing 3, as previously described and flows through the inner tubes 39, to take part in the heat exchange. Baffles 40 between the intermediate headers 31 and 37 guide the air, which has flowed through the inner tubes 39, into the spaces 12b for air which has taken its part in the heat exchange, forming with baffles 41, 42 and 44, 45 the system of baffles which, together with sidewalls 10 of spaces 12c prevents any air which has not yet taken part in the heat exchange from entering said spaces 12b.

In both the embodiments described with reference to Figs. 4 and 5 to Figs. 6 and 7, a duct will surround the assembly, the function of the duct being the same as those of the duct described with reference to Figs. 1 and 2 for a forced convection heat exchanger, or as described with reference to Fig. 3 for a natural convection heat exchanger. Both these embodiments will be suitable for applications where the fluid flowing inside the tubes is to be divided into two separate quantities, each of which has to experience a different temperature change.

In the examples described, it will have been noted that the surfaces on which respectively are situated the centre-lines of the tubes of a row, which surfaces may, according to this invention be closed in themselves, as, for example, cylinders, have generating lines which are substantially straight lines in at least one direction, and the entry and exit cross-sections for the fluid normal to these generating lines into and respectively out of the spaces between the rows of tubes is left unobstructed, for the following reasons:

(1) In order to prevent pressure losses due to changes of flow-direction in the fluid flowing outside the tubes, particularly in cases of natural convection providing the motion of this fluid.

(2) In order to prevent uneven distribution of the fluid flow on the heat transferring walls, which would arise due to centrifugal forces acting at changes of the flow-direction, and which would reduce the effective area of heat transferring wall for heat exchange.

(3) In order that, quite generally, the flow-path of the fluid from the entry to the heat exchanger to the exit from the heat exchanger should be shortest, and

(4) In order to keep the cross-sectional area normal to the flow-direction of the duct which surrounds the whole assembly, in as small a ratio as possible to the actual total cross-section of this fluid into the spaces between the rows of tubes (and similarly the ratio between the cross-section for the fluid in the duct after the heat exchanger to the actual total exit cross-sections of the fluid from the passages between rows of tubes), so that pressure losses due to sudden changes of cross sectional area of flow are kept as low as possible.

Thus, in embodiments of the invention, the fluid flowing outside the passages (tubes) will be guided by guide-walls and guide-vanes in such a way, that for the periods that layers of this fluid

are actually taking direct part in the heat exchange, i.e. are in contact with the heat transferring wall, the centres of gravity of these layers anywhere along their flow in contact with heat transferring wall, are on substantially straight lines.

In order to provide for layers being led away from the heat transferring wall when they have taken their part in the heat exchange, and other layers, which have not yet been in contact with heat transferring wall, being led into contact with heat transferring wall, each row of tubes is provided with a guide-wall substantially surrounding it, and open at either end to allow entry and exit for the fluid flowing outside the tubes. These guide walls, at different positions along the flow of the fluid layers in contact with a heat transferring wall, will have slots running normally to this flow direction, or other suitable openings, to provide exits and respectively entries for such layers. In preferred embodiments, using the same guide-vane to lead layers of fluid away from a heat transferring wall with its one side and other layers into contact with a continuation of heat transferring wall with its other side, the exits for the fluid layers which have taken their part in the heat exchange are arranged to one side of this row of tubes, while the entries for the fluid layers which have not yet taken part in the heat exchange are arranged on the other side of this row of tubes.

The rows of tubes making up a heat exchanger, with their surrounding guide-casings, will in preferred embodiments be so arranged relatively to one another, that the entries for adjacent rows of tubes face one another across a space between the guide-walls of these rows, and similarly the exit slots of adjacent rows of tubes face one another across another such space between two guide-walls. Accordingly, every second space between adjacent rows of tubes will have fluid flowing in it which has not yet been in contact with a heat transferring wall, which is being led off in layers to the rows of heat exchange elements at either side to come into contact with a heat transferring wall at different positions along the flow of such layers, while every other second space will have fluid flowing in it which has already taken its part in the heat exchange, having been guided into said space from both rows of tubes at different positions. The walls forming the spaces carrying fluid which has already taken its part in the heat exchange will be so closed, that no layers of fluid which have not been in contact with a heat transferring wall can enter into such spaces.

In preferred embodiments of this invention, the generating lines of the centre-line surfaces of adjacent rows of tubes will be somewhat inclined to one another, so that passages between rows of tubes which carry fluid which has not yet taken part in the heat exchange and is led away along the length of the passages get narrower in the flow-direction, while the passages carrying fluid which has taken its part in the heat exchange get wider in the flow direction.

In construction of the heat exchangers in accordance with the invention, different positions on the heat transferring wall or walls along the flow of the fluid flowing outside the passages or tubes, are brought into contact with different layers of this fluid, which have not yet taken part in the heat exchange, and in this way, one and the same volume of the fluid flowing inside the passages or tubes, will in its passage through the

tubes, come into heat exchange proximity in consecutive intervals of time with layers of the outside fluid, which have not yet taken part in the heat exchange and thus substantially still have their initial temperature, so that in this way the temperature difference through the heat transferring wall is kept high particularly for special cases where in the fluid inside the tubes has the high specific heat per unit volume, while the outside fluid has a low specific heat per unit volume, without velocities being increased, and in this way the mean rate of heat transfer per unit area of heat transferring wall taken over the whole wall, is made high.

The provisions described in the foregoing are very important from other points of view as well, viz.: from the point of view of the uniformity of the heating of the fluid flowing outside the tubes; from the point of view of reducing the pressure-losses of the fluid flowing outside the tubes; from the point of view of bringing about effective heat exchange between a liquid of high specific heat per unit volume inside the tubes and air or another gas flowing outside the tubes, where this gas has a very much smaller specific heat per unit volume (for the cases of water inside and air outside the tubes, the ratio of the specific heats per unit volume may be about 3000 to 1); and finally from the point of view of efficient exploitation of the natural convection as moving agent for the cooling air, leading e. g. to economical designs of coolers of large capacity without fan-draught for the cooling air, and making atmospheric air applicable as cooling agent instead of water for certain applications.

It will be understood that the embodiments of my invention described in the foregoing are by way of example only, and that many other examples and modifications of the invention are possible within the scope of the appended claims.

I claim:

1. In and for a heat exchanger the combination of a row of heat exchange elements respectively bathed externally by a first fluid and traversed internally by a second fluid taking part in the heat exchange, of a guide-casing for said first fluid around said row of heat exchange elements with an entry for said first fluid at one end and an exit for said first fluid at its other end, and of an entry guide means and an exit guide-means in the walls of said guide-casing situated between the entry and exit ends of said guide-casing, at a position along the length of at least one of the heat exchange elements of said row, for diverting at least a layer of said first fluid which has flowed in immediate heat exchange proximity with only a part of said one element and has taken its part in the heat exchange, away from said element to outside said casing, and for guiding a layer of said first fluid, which has flowed outside said guide-casing and has not yet been in contact with a heat exchange element into immediate heat exchange proximity at least with said one heat exchange element of said row on its continuation to flow therealong in the same direction in which flowed the layer which has been diverted from said element.

2. In and for a heat exchanger, the combination as claimed in claim 1, in which said entry and exit guide-means are in direct contact with at least said one heat exchange element of said row.

3. In and for a heat exchanger, the combination as claimed in claim 1, in which said entry and exit guide-means in the walls of said guide-

casing are respectively disposed along the entire width of said guide-casing on opposite side-walls thereof.

4. In and for a heat exchanger, the combination as claimed in claim 1, in which said entry and exit guide-means comprise slots in opposite side-walls of said casing, said slots extending respectively the entire width of said guide-casing, and a vane connecting one edge of the entry-slot with the other edge of the exit-slot in a gradual transition, said guide-vane gradually diverting with one side-surface layers of fluid, which have flowed in immediate heat exchange proximity substantially along said heat exchange elements of said row and have taken their part in the heat exchange to outside said guide-casing on one side, and said guide-vane with its opposite side-surface guiding layers of fluid, which have flowed outside said guide-casing on its other side and have not yet been in heat exchange proximity with a heat exchange element into immediate heat exchange proximity with said elements of said row on their respective continuations.

5. In and for a heat exchanger, the combination of a plurality of rows of heat exchange elements, which are respectively bathed externally by a first fluid and traversed internally by a second fluid taking part in the heat exchange, of a plurality of guide-casings for said first fluid, each arranged around a row of said elements, and having each an entry for said first fluid at one end and an exit for said first fluid at its other end, and of at least one entry guide-means and exit guide-means for said first fluid in opposite side-walls and situated between the entry and exit end of said casing at a position along the length of said heat exchange elements of said row, for diverting layers of said first fluid which have flowed in immediate heat exchange proximity substantially along the elements of said row and have taken their part in the heat exchange away from said elements out of said casing to one side thereof, and for guiding layers of said first fluid which have flowed outside said guide-casing on its other side and have not yet flowed in heat exchange proximity with a heat exchange element into immediate heat exchange proximity with said elements of said row on their respective continuations to flow therealong in the same direction in which flowed the layers which have been diverted from said elements, said rows of heat exchange elements with their guide-casings being spaced adjacent one another so that for adjacent rows said entry and respectively exit guide-means face one another across alternate spaces between guide-casings of adjacent rows of elements, each alternate space between two guide-casings into which face exit guide-means thus forming an exit-space and containing said first fluid which has already taken part in the heat exchange, and every other alternate space between two such guide-casings into which face entry guide-means thus forming an entry-space and containing said first fluid which has not yet taken part in the heat exchange, the said combination further comprising side-walls at least for said exit-spaces, which side-walls extend between adjacent guide-casings, and baffles situated substantially at one end of said space for at least said exit-spaces, for separating said exit-spaces from said entry-spaces.

6. In and for a heat exchanger, the combination as claimed in claim 5, in which said heat exchange elements have entry and exit header tanks respectively common to each row for said

second fluid flowing internally through said heat exchange elements and taking part in the heat exchange.

7. In and for a heat exchanger, the combination as claimed in claim 5, in which said heat exchange elements are tubes having entry and exit header tanks respectively common to each row of tubes for said second fluid flowing internally through said tubes and taking part in the heat exchange, said entry and respectively exit header tanks for every adjacent pair of rows being disposed in staggered relationship to one another.

8. A heat exchanger comprising a duct, a plurality of rows of heat exchange elements within said duct, said elements being respectively bathed externally by a first fluid traversing said duct and traversed internally by a second fluid taking part in the heat exchange, a plurality of guide-casings for said first fluid each arranged around a row of said elements and having each an entry for said first fluid at one end and an exit for said first fluid at its other end, and at least one entry-guide-means and exit guide-means for said first fluid in opposite side-walls and situated between the entry and exit ends of said casing at a position along the length of said heat exchange elements of said row, for diverting layers of said first fluid which have flowed in immediate heat exchange proximity substantially along the elements of said row and have taken their part in the heat exchange away from said elements out of said casing to one side thereof, and for guiding layers of said first fluid which have flowed outside said guide-casing on its other side and have not yet flowed in heat exchange proximity with a heat exchange element into immediate heat exchange proximity with said elements of said row on their respective continuations, to flow therealong in the same direction in which flowed the layers which have been diverted from said elements, said rows of heat exchange elements with their guide-casings being spaced adjacent to one another so that for adjacent rows said entry and respectively exit guide-means face one another across alternate spaces between guide-casings of adjacent rows of elements, each alternate space between two guide-casings, into which face exit guide-means thus forming an exit-space and containing first fluid which has already taken part in the heat exchange, and every other alternate space between two such guide-casings, into which face entry guide-means, thus forming an entry-space containing first fluid which has not yet taken part in the heat-exchange, the said heat exchanger further comprising the side-walls at least for said exit-spaces, which side-walls extend between adjacent guide-casings, and baffles situated substantially at least one end of said exit and entry spaces, the said baffles at the ends of said entry-spaces extending to the wall of said duct, for separating space in said duct which contains said first fluid before it has taken part in the heat exchange from space in said duct which contains said first fluid after it has taken part in the heat exchange.

9. A heat exchanger as claimed in claim 8, in which the surfaces containing the middle-lines of the heat exchange elements of said rows have substantially vertically directed generating lines, and in which said duct surrounding the assembly ends in a chimney, the said first fluid flowing through the said heat exchanger by virtue of natural convection only.

10. A heat exchanger as claimed in claim 8, in which said heat exchange elements are tubes hav-

ing entry and exit header tanks respectively common to each row of tubes for said second fluid flowing internally through said tubes and taking part in the heat exchange, said entry and respectively exit header tanks for every adjacent pair of rows being disposed in staggered relationship to one another, and the surfaces containing the middle-lines of the heat exchanger tubes of said rows having substantially vertically directed generating lines, and said duct surrounding the assembly ending in a chimney, the said first fluid flowing through the heat exchanger by virtue of natural convection only.

11. A heat exchanger comprising at least two sets of rows of heat exchange elements, each forming a heat exchanger as claimed in claim 8, arranged one after the other in the flow-direction of said first fluid with said duct common to both, the said heat exchange elements being tubes of step-wise increasing diameters for consecutive rows of tubes of the said sets, a header tank disposed between and common to each two such consecutive rows of tubes, the tubes of the rows of larger diameter tubes debouching thereinto and the smaller diameter tubes of the consecutive row passing therethrough into the mouths of the larger-diameter tubes of said first-mentioned row, said header tanks serving to lead away out of the heat exchanger the outer layers of the second fluid flowing inside said tubes of said consecutive rows from said larger-diameter tubes to said smaller diameter tubes, while the inner layers of said fluid continue to flow in the smaller diameter tubes of the consecutive row.

12. A heat exchanger comprising two sets of rows of heat exchange elements, each forming a heat exchanger as claimed in claim 8, arranged one after the other in the flow direction of said first fluid with the said duct common to both, the said heat exchange elements of each row being tubes having entry and exit header tanks respectively common to each row of tubes for said second fluid flowing internally therethrough, said heat exchanger further comprising smaller diameter tube-stumps passing from the mouths of the tubes of a row through the exit header tanks of this row into the entry header tanks of the consecutive row of tubes, the outer layers of the flow of said second fluid in the tubes of said first-mentioned row flowing outside said tube-stumps into the exit header tank of this row, which leads them out of the heat exchanger, while the inner layers of flow of the second fluid in the respective tubes flow through said tube-stumps into the entry header tank of the consecutive row of tubes, the tubes of said consecutive row being on centre-lines different from those of the tubes of the first row and being provided with smaller diameter inner tubes which

pass through the entry and exit header tanks of this row, the annular spaces between said tubes and said inner tubes of said row being traversed by said second fluid taking part in the heat exchange, while the inner tubes themselves are traversed by said first fluid which also bathes externally the tubes of all rows, said heat exchanger further comprising baffles between the exit header tank of one row of tubes and the entry header tanks of the consecutive row of tubes, for guiding layers of said first fluid which have flowed through said smaller diameter inner tubes of a row into the exit space formed between the guide-casing of this and of a laterally adjacent row, said baffles further serving to separate such exit-spaces, in which flows fluid which

has taken part in the heat exchange from entry spaces which contain first fluid which has not yet taken part in the heat exchange.

13. A heat exchanger comprising a duct, a row of heat exchange elements respectively bathed externally by first fluid traversing said duct and traversed internally by a second fluid taking part in the heat exchange, a guide-casing for said first fluid around said row of heat exchange elements with an entry for said first fluid at one end and an exit for said first fluid at its other end, and an entry guide-means and an exit guide-means in the walls of said guide-casing and situated between the entry and exit ends thereof, at a position along the length of at least one of said heat exchange elements of said row, for diverting at least a layer of said first fluid which has flowed in immediate heat exchange proximity with only a part of said one element and has taken its part in the heat exchange, away from said element to outside said guide-casing, and for guiding a layer of said first fluid which has flowed outside said guide-casing and has not yet been in contact with a heat exchange element into immediate heat exchange proximity at least with said one heat exchange element of said row on its continuation, to flow therealong in the same direction in which flowed the layer which has been diverted from said element, the said heat exchanger further comprising baffles connecting said guide-casing and the wall of said duct for separating space in said duct and outside said guide-casing which contains first fluid before it has taken part in the heat exchange from space in said duct and outside said guide-casing which contains first fluid which has not yet taken part in the heat exchange.

14. A heat exchanger as claimed in claim 13, in which said entry and exit guide-means comprise slots in opposite side-walls of said guide-casing, said slots extending respectively the entire width of said guide-casing, and a vane connecting one edge of the entry-slot with the other edge of the exit-slot in a gradual transition, said guide-vane gradually diverting with one side-surface layers of fluid, which have flowed in immediate heat exchange proximity substantially along said heat exchange elements of said row and have taken their part in the heat exchange, to outside said guide-casing on one side, and said guide-vane with its other side-surface guiding layers of fluid which have flowed outside this guide-casing on its other side and have not yet been in proximity with a heat exchange element into immediate heat exchange proximity with said elements of said row on their respective continuations.

15. A heat exchanger comprising a duct, a plurality of rows of heat exchange elements within said duct, said elements being respectively bathed externally by a first fluid traversing said duct, and traversed internally by a second fluid taking part in the heat exchange, a plurality of guide-casings for said first fluid, each arranged around a row of said elements and having each an entry for said first fluid at one end and an exit for said first fluid at its other end, and at least one entry-guide-means and an exit guide-means for said first fluid in opposite side-walls and situated between the entry and exit ends of said casing at a position along the length of said heat exchange elements of said row, for diverting layers of said first fluid which have flowed in immediate heat exchange proximity substantially along the elements of said row and have

taken their part in the heat exchange away from said elements out of said casing to one side thereof, and for guiding layers of said first fluid which have flowed outside said guide-casing on its other side and have not yet flowed in heat exchange proximity with a heat exchange element into immediate heat exchange proximity with said elements of said row on their respective continuations, to flow therealong in the same direction in which flowed the layers which have been diverted from said elements, said rows of heat exchange elements with their guide-casings being spaced adjacent to one another so that for adjacent rows said entry and respectively exit guide-means face one another across alternate spaces between guide-casings of adjacent rows of elements, each alternate space between two guide-casings into which face exit guide-means thus forming an exit-space and containing first fluid which has already taken part in the heat exchange, and every other alternate space between two such guide-casings into which face entry guide-means thus forming an entry-space containing first fluid which has not yet taken part in the heat exchange, the said guide-casings extending up to the walls of said duct, and the said heat exchanger further comprising baffles situated substantially at at least one end of each of said spaces and extending between adjacent guide-casings and up to the wall of said duct, for separating space in said duct which contains first fluid before it has taken part in the heat exchange from space in said duct which contains first fluid after it has taken part in the heat exchange.

16. A heat exchanger as claimed in claim 15, in which the surfaces containing the middle-lines of the heat exchange elements of said rows have substantially vertically directed generating lines, and in which said duct surrounding the assembly ends in a chimney, the said first fluid flowing through the heat exchanger by virtue of natural convection only.

17. A heat exchanger as claimed in claim 15, in which said heat exchange elements are tubes having entry and exit header tanks respectively common to each row of tubes for said second fluid flowing internally through said tubes and taking part in the heat exchange, said entry and respectively exit header tanks for every adjacent pair of rows being disposed in staggered relationship to one another; in which the surfaces containing the middle-lines of the heat exchanger elements of said rows have substantially vertically directed generating lines, and in which said duct surrounding the assembly ends in a chimney, the said first fluid flowing through the heat exchanger by virtue of natural convection only.

18. A heat exchanger as claimed in claim 15, in which said heat exchange elements are tubes having entry and exit header tanks respectively common to each row of tubes for said second fluid flowing internally through said tubes and taking part in the heat exchange, said entry and respectively exit header tanks for every adjacent pair of rows being disposed in staggered relationship to one another.

19. A heat exchanger as claimed in claim 15, in which said heat exchange elements are tubes having entry and exit header tanks respectively common to each row of tubes, said tubes being traversed by smaller diameter tubes passing through the header tanks of said row of tubes,

15

said header tanks serving the annular spaces between said outer and inner tubes with said second fluid taking part in the heat exchange, said first fluid taking part in the heat exchange also flowing through said smaller diameter inner tubes.

MEYER FRENKEL.
